UNITED STATES PATENT OFFICE.

FREDERICK J. BOWERY, OF PITTSBURG, PENNSYLVANIA, ASSIGNOR TO THE McCONWAY & TORLEY COMPANY, OF PITTSBURG, PENNSYLVANIA, A CORPORATION OF PENNSYLVANIA.

CAR-COUPING.

No. 839,101.

Specification of Letters Patent.

Patented Dec. 25, 1906.

Application filed September 21, 1906. Serial No. 335,582.

To all whom it may concern:

Be it known that I, FREDERICK J. BOWERY, a citizen of the United States, residing at Pittsburgh, in the county of Allegheny and State of Pennsylvania, have invented certain new and useful Improvements in Car-Couplings; and I do hereby declare the following to be a full, clear, and exact description of the invention, such as will enable others skilled in the art to which it appertains to make and use the same.

My invention relates to the construction of car-couplers of the vertical-plane or Master Car-Builders' type, and has for its object to provide such a form and arrangement of the locking mechanism for the knuckle thereof that a strong, light, compact, and efficient structure results.

The invention is illustrated as embodied in a car-coupler in which the coupler-head is adapted to be flexibly mounted upon one or more stems, draw-bars, brackets, or equivalent parts, since said invention is particularly applicable to such a structure and may be advantageously used therewith. These several desired objects are attained by combining with a coupler-head and its pivoted knuckle a spring-pressed lock or catch which is mounted on a vertical pivot upon the knuckle side of the coupler-head and which is adapted to be brought to an unlocked position through the intermediary of a lever, which is also mounted on the coupler-head by means of a vertical pivot at or near the center of said head, and such a construction embodies one feature of my invention.

There are other features of invention residing in elemental combinations and particular constructions, all as will hereinafter more fully appear.

In the drawings chosen for the purpose of illustrating my invention, the scope whereof is pointed out in the claims, Figure 1 is a plan view of a car-coupler embodying my invention, a part of the head being broken away to show the relative position of the knuckle and knuckle-locking mechanism when the parts are in a locked position. Fig. 2 is a side elevation of the coupler shown in Fig. 1. Fig. 3 is a horizontal central section of the coupler, the locking mechanism being shown in plan, in an unlocked position. Figs. 4, 5, and 6 are enlarged detail views illustrating the

knuckle lock or catch in front elevation, plan, and side elevation, respectively. Figs. 7, 8, 55 and 9 are enlarged detail views illustrating the lock or catch actuating lever in plan, side elevation, and rear elevation, respectively.

Like symbols refer to like parts wherever 6c they occur.

I will now proceed to describe my invention more fully, so that others skilled in the art to which it appertains may apply the same.

In the drawings, 1 is a coupler-head, to which the knuckle 2 is attached in the usual manner by the knuckle-pin 3, said knuckle-pin, if desired, being inserted from below and retained in position by knuckle-pin plate 3^a, 70 as shown. The coupler-head illustrated is constructed with a pocket 4, formed in the rear face thereof, said pocket being for the purpose of receiving a draw-bar, which is adapted to be flexibly attached to said head 75 1 by a pivot-pin 5 located in the median line of the head. When a coupler-head of the form heretofore described is employed, the pin 5 may also serve as a pivot for the catch or lock actuating lever 10, it being preferred 80 to form said pivot-pin 5 with a collar 6, which abuts the under face of the coupler-head and between which and the nut on the lower end of the said pivot-pin 5 the lever 10 is mounted. Upon the knuckle side of the coupler-head 85 means are provided for pivotally attaching to said head the horizontally-movable lock or catch 9, which operates to retain the knuckle 2 in coupled position, said means preferably consisting of a pivot-pin passing through 90 said catch 9 and through perforated lugs 7, which are disposed opposite the lock-abutment 8 of the coupler-head and adjacent to the inner or lock-engaging end of the knuckle.

Pivotally attached to the coupler-head, as 95 before described, is the horizontally-rotatable lock or catch 9, which when in a locked position is interposed between the locking-face 2^a of the knuckle and the lock-abutment 8 of the coupler-head and which through the intermediary of the lock-lever or catch-lever 10 may be rotated backward against the pressure of the spring 11 a sufficient distance to permit the knuckle 2 to move outwardly to an open position. This lock or catch is preferably 100 constructed with perforated lugs 9^a, which are

interposed between the lugs 7 of the coupler-head and are attached thereto by means of the pivot-pin, which passes through each of the several lugs referred to, such a construction enabling light castings to be used and also permitting ready inspection of the locking mechanism.

The body portion of the lock 9 is formed with a pocket or recess 9^b, which receives the inner end of the knuckle when the several parts of the coupler are in coupled relation, the end wall 9^c of the catch 9 then being interposed between the locking-face 2^a of the knuckle-tail and the lock-abutment 8 of the coupler-head. The recess 9^b of the lock or catch 9 is preferably open adjacent to the perforated lugs 9^a of said lock, as such a construction permits the locking end of the knuckle 2 to be seen when the parts are in locked position. For this purpose the lock 9 is formed with horizontally-extending top and bottom walls 9^d and with a rear wall 9^e, said walls extending between the end wall or locking-wall 9^c of the lock and the perforated lugs 9^a thereof.

Formed upon the rear wall 9^e of the lock 9 and projecting rearwardly therefrom is a cup-shaped spring-seat 9^f, which is provided with a central pin or lug, that is adapted to enter the bore of the spring 11, the said spring-seat being somewhat elongated and having inclined end walls and the central pin or lug being also inclined to permit the said spring to be compressed lineally without lateral distortion when the lock or catch 9 is rotated backward to an unlocked position.

As a means of forming an operative connection with the upwardly-extending pin or post 10^a of the catch-lever 10 the end wall 9^c of the catch 9 is formed with a recess 9^g, which extends upwardly from the under side of said catch at a point slightly to the rear of the recess 9^b thereof, said recess or socket 9^g, as shown, being somewhat elongated in cross-section, so as to permit the post 10^a to approach or recede from the pivotal center of the said catch 9 when the latter is moved to locked or unlocked position. The outer portion of the end or locking wall 9^c of the catch 9 is rounded or beveled, as at 9^h, so that the said catch may be forced rearwardly by the engagement of the curved face 2^b of the knuckle 2 therewith when the latter moves from an uncoupled to a coupled position.

Pivotedly mounted upon the coupler-head 1, as by being mounted on the vertical pivot-pin 5 at the center of the head, as heretofore described, is the bell-crank catch-lever or lock-lever 10, said lever having an arm which extends toward the pivoted catch or lock 9 and which is provided with a vertical post 10^a, which enters the socket 9^g of the lock 9. The other and preferably longer arm of the catch-lever 10 may be provided with any suitable means—as, for example, the hole 10^b—for

forming a connection with the usual or any desired form of uncoupling device such as is operated from the platform or side of a car.

To facilitate the introduction of the lock or catch operating post 10^a into the socket 9^g of the lock or catch 9 to minimize the friction between said catch and post, to relieve the said post from excessive strain, and to permit the pin-and-socket connection between the catch 9 and catch-lever 10 to compensate for inequalities in the pivoting of said catch and catch-lever, the said operating pin or post 10^a is preferably tapered vertically, so that it is of slightly less diameter at its upper end than at its base.

As a means for normally maintaining the pivoted lock 9 in locked position a spiral spring 11 is employed, said spring being housed within the coupler-head 1 and having one end seated upon the spring-seat 9^f of the catch 9. The other end of the spring 11 bears against the rear wall of the coupler-head and is maintained in relation therewith by means of the lug 1^a, which is so inclined as to permit the said spring 11 to change the inclination of its axis without bending transversely.

Having thus described my invention, what I claim, and desire to secure by Letters Patent, is—

1. In a car-coupler, the combination with a coupler-head, of a knuckle pivotally mounted thereon, a lock pivotally mounted upon the knuckle side of said head, said lock having a pocket which receives the locking end of said knuckle when the parts are in locked position and also having an elongated spring-seat provided with inclined end walls, and a spiral spring engaging said lock and said head and adapted to be compressed lineally without lateral distortion when the lock is moved to an unlocked position.

2. In a car-coupler, the combination with a coupler-head, of a knuckle pivotally mounted thereon, and a pivotally-mounted lock for said knuckle, said lock having an end wall, a rear wall, and top and bottom walls, said walls forming a pocket for the reception of the locking end of the knuckle when the parts are in a locked position and said end wall being beveled to permit the said lock to be forced rearwardly by the knuckle when the latter is moved from an open to a closed position.

3. In a car-coupler, the combination with a coupler-head, of a knuckle pivotally mounted thereon, a lock pivotally mounted upon said head, and a lock-actuating lever pivotally mounted upon said head, said lock and said lever having a pin-and-socket connection the pin whereof is tapering.

4. In a car-coupler, the combination with a coupler-head which is adapted to be pivotally connected to a draw-bar or the like, of a knuckle, a pivotally-mounted lock, and a

lock'-actuating lever which is pivotally mounted on said head at the point of draw-bar connection.

5. In a car-coupler, the combination with a coupler-head which is adapted to be pivotally connected to a draw-bar or the like, of a pivotally-mounted knuckle, a lock mounted on a vertical pivot at the knuckle side of said head, a lock-actuating lever which is pivotally mounted on a vertical pivot at the point

of draw-bar connection with said head, and a spring which normally maintains said lock in locked position.

In testimony whereof I affix my signature in presence of two subscribing witnesses.

FREDERICK J. BOWERY.
